Wayne M. Hart
ATTORNEY.

UNITED STATES PATENT OFFICE.

CHARLES C. SPREEN, OF DETROIT, MICHIGAN, ASSIGNOR TO KELVINATOR CORPORATION, OF DETROIT, MICHIGAN, A CORPORATION OF MICHIGAN.

REFRIGERANT-CONTROL MECHANISM.

Application filed January 29, 1927. Serial No. 164,484.

This invention relates to mechanical refrigerating mechanism, and more particularly to mechanism for controlling the passage of liquid refrigerant into the evaporator.

- 5 In mechanical refrigerating mechanism of the flooded type wherein a constant quantity of liquid refrigerant is maintained in the evaporator, it is customary to provide a control mechanism mounted either interiorly of 10 the evaporator or in a reservoir adjacent the evaporator which includes a float actuated valve element co-operating with a liquid refrigerant supply passage. The support for the float and valve element is fixed interiorly 15 of the evaporator or reservoir to a removable plate through which refrigerant inlet and outlet passages usually extend. Difficulty has been encountered in maintaining a tight seat for the valve element due to wear caused by 20 the extensive movement of the hardened valve element against its seat which is formed at the end of the inlet passage in the removable plate, usually a casting.

An object of this invention is to provide co- 25 operating valve mechanism elements for controlling the passage of liquid refrigerant into an evaporator of refrigerating mechanism which will withstand extensive use without deforming their seating faces.

30 Another object of this invention is to provide removable co-operating valve mechanism elements for controlling the passage of liquid refrigerant into an evaporator of refrigerating mechanism so that the parts can be replaced and thus reduce the cost of servicing.

35 A further object of the invention resides in the construction and association of valve mechanism elements with a removable portion of an evaporator which facilitates assembly and servicing and reduces the cost of such operations.

40 Further objects and advantages of the present invention will be apparent from the following description, reference being had to the 45 accompanying drawing wherein a preferred form of embodiment of the present invention is clearly shown.

In the drawing:

50 Fig. 1 is a partial sectional view of an evaporator having my improved mechanism associated therewith;

Fig. 2 is a sectional view taken on line 2-2 of Fig. 1 showing the manner of attaching the valve supporting structure, and

Fig. 3 is a perspective view of the bracket 55 which carries the float and valve element.

Referring to the drawings by characters of reference 10 represents a vessel for containing liquid refrigerant which is commonly known as an evaporator. The evaporator is 60 connected in circuit with a compressor and condenser, and the refrigerant enters the evaporator in liquid form and is vaporized as heat surrounding the evaporator is absorbed. This type of refrigerating apparatus is well 65 known and a further description is not deemed necessary herein.

The evaporator consists of a cylindrical vessel which terminates in an open end to which an annular ring or collar 11 is fixed in 70 leak-proof relation by solder 12. A lead gasket 13 is placed adjacent the outer end of the collar, and a removable cast metal wall 14 is drawn against the lead gasket by studs 15 which extend through the wall and screw into 75 the end of the collar. A boss 16 extends interiorly of the collar from the inner surface of the removable wall and a refrigerant inlet passage 17 extends through the removable wall and boss. A refrigerant outlet passage 80 18 extends preferably through the upper portion of the removable wall, and suitable couplings 18^a and 19 are secured to the removable wall adjacent respectively the inlet and outlet passages for connecting the same with refrigerant supply and return conduits which extend 85 to the compressing and condensing apparatus. A wire screen 20 is secured within the outer portion of the inlet passage in the removable wall of the evaporator to prevent 90 the passage of foreign matter such as dirt, scales, etc. which may accumulate in the refrigerant.

Mechanism for controlling the flow of liquid refrigerant is attached to the removable 95 wall of the evaporator and can be removed therewith. A valve seat 21 is pressed into the inner end of the inlet passage 17 in the end of the boss 16 and is provided with a flanged end 22 to limit the insertion. The valve seat is 100 formed of hardened metal and is provided with an axially extending passage through

which the liquid refrigerant flows into the liquefied refrigerant, said vessel having inlet and outlet refrigerant passages extending through its wall, a removable valve seat disposed within said inlet passageway and an individually removable unitary valve mechanism secured to the interior wall of said vessel adjacent said inlet passage, said valve mechanism including a valve element, a float for actuating said valve element and a carrier. 70

5 A unitary valve mechanism is removably 10 mounted interiorly of the vessel to the removable wall and is arranged to automatically open and close the valve seat to maintain a constant level of liquid refrigerant. A supporting bracket consisting of a base 23 having an annular flange extending from one side and arms 24 extending from the other side provide a support for the needle valve element 25 and the float lever 26. The float arm is supported on a pivot 27 at one end between the arms 24 and a float member 28 is 15 secured to the other end of the lever 26. The bracket base is provided with an aperture 29 registering with the passage in the valve seat and the needle valve is reciprocated there-through to open and close the passage in the valve seat. The valve element is secured at its interior and to a pivot 30 which is fixed to ears 31 projecting from the float lever. It will be seen that the float arm and valve element are carried by the bracket, and the bracket is removably attached to the end of the boss by studs 32. The flanged portion of the bracket extends around the end of the annular boss providing a mounting which 20 relieves the tension on the studs 32 and assists in maintaining the valve element in position to co-operate with the valve seat. The base of the bracket is arranged to bear against and thus retain the removable valve seat in 25 assembled position. It will be seen that the float moves downwardly as the liquid refrigerant boils off, that is, becomes vaporized when absorbing heat, which actuates the valve element to admit liquid refrigerant into the vessel. As the level of the liquid rises, the float moves therewith and shuts off the supply line and such reciprocation of the valve element is almost constant during the absorption of heat by the refrigerant. 30

50 It will be seen that the valve mechanism and the valve seat can be readily attached and detached from the wall when desired, thus giving economy in manufacture and service. It will also be seen that the valve mechanism is removable from the vessel with the end wall which also is an advantage and saving in the manufacture and servicing of the device.

Various changes can be made in the details 60 of the device herein described without departing from the spirit of my invention and the scope of what I claim.

What I claim is:

1. In refrigerating apparatus of the class 65 described, a vessel adapted to contain a liq-

uefied refrigerant, said vessel having refrigerant passages through its wall, a removable valve seat extending into the interior end 80 of the inlet passage in said vessel, a valve element in said vessel arranged to co-operate with said seat, float mechanism for actuating said valve element, and a bracket removably secured to the wall of said vessel positively 85 retaining said valve seat in said passage, said bracket carrying said valve element and said float mechanism. 95

3. In refrigerating apparatus of the class 100 described, a vessel adapted to contain a liquefied refrigerant, said vessel having a removable wall having refrigerant inlet and outlet passages therethrough, a removable hardened valve seat extending into the interior end of said inlet passage, a bracket removably secured to the interior of the removable wall of said vessel over said valve seat, a valve element adapted to open and close the passage through said valve seat and carried by said bracket, and float mechanism for actuating said valve element carried by said bracket. 105

4. In refrigerating apparatus of the class 110 described, a vessel adapted to contain a liquefied refrigerant, having a removable wall, an inwardly extending boss on said wall having a refrigerant passage extending therethrough, a refrigerant outlet passage through a wall of said vessel, a removable valve seat in the passage in said boss, a reciprocable 115 valve element arranged to co-operate with said seat, float mechanism pivotally connected to actuate said valve element, and a bracket for supporting said valve element and float mechanism, said bracket being removably secured to the end of said boss. 120

5. In refrigerating mechanism of the class 125 described, a vessel for containing liquefied refrigerant, said vessel having a refrigerant outlet passage, a removable wall for said vessel, an annular boss extending interiorly from said removable wall having a refrigerant inlet passage extending therethrough, a removable valve seat in said boss passage, said valve seat having a flange to engage said boss and limit the insertion thereof within said passage, a bracket having a flange extending around the end portion of said boss and a base fitting against the flanged end of said valve seat and the end of said boss, said 130

bracket base having an opening there-through registering with the valve seat, arms extending from said bracket, a valve element reciprocable through the opening in said bracket base, float mechanism for actuating said valve element, said valve element and said float mechanism being carried by said

5 bracket, arms, and means for removably securing the base of said bracket to the end of said boss.

10 In testimony whereof, I hereunto affix my signature.

CHARLES C. SPREEN.
